Webster & Elliott LLP(57) **CLAIM**

The ornamental design for a surveillance camera, as shown and described.

DESCRIPTION

FIG. 1 is a front perspective view of a surveillance camera;
 FIG. 2 is a front elevation view thereof;
 FIG. 3 is a back elevation view thereof;
 FIG. 4 is a right side elevation view thereof;
 FIG. 5 is a left side elevation view thereof;
 FIG. 6 is a top plan view thereof; and,
 FIG. 7 is a bottom plan view thereof.
 The broken lines depict portions of the surveillance camera
 in which the design is embodied that form no part of the
 claimed design.
